UNITED STATES PATENT OFFICE.

REUBEN E. NICHOLS, OF PHILADELPHIA, PENNSYLVANIA.

CAR-HEATER.

SPECIFICATION forming part of Letters Patent No. 430,875, dated June 24, 1890.

Application filed December 6, 1889. Serial No. 332,763. (No model.)

To all whom it may concern:

Be it known that I, REUBEN E. NICHOLS, a citizen of the United States, residing in the city and county of Philadelphia, State of Pennsylvania, have invented a new and useful Improvement in Car-Heaters, which improvement is fully set forth in the following specification and accompanying drawings.

My invention relates to car-heaters; and it consists of the construction, arrangement, or combination of the parts, as will be more fully hereinafter set forth and definitely claimed.

Figure 1 represents a vertical section of a locomotive-engine containing part of a car-heater embodying my invention. Fig. 2 represents a front view of portion of the heater and adjacent parts of the engine. Fig. 3 represents a partial side elevation and partial longitudinal section thereof. Figs. 4 and 5 represent longitudinal sections of portions of cars with parts of my invention applied thereto.

Similar letters of reference indicate corresponding parts in the several figures.

Referring to the drawings, A designates the smoke or fire box of a locomotive-engine, and B designates a chamber for heating air, the same being located in said box and consisting of a suitable casing, to the front and rear walls of which are secured flues C, which admit the passage of the products of combustion through the same, it being seen that the products of combustion also pass around the casing, whereby the casing will be highly heated without, however, affecting the draft.

D represents nozzles or pipes, which pass tightly through the shell of the boiler, and are connected with the casing of the chamber B, so as to be in communication therewith and direct air thereinto.

A' designates a neck, which unites the two divisions of the chamber B.

E designates pipes, which are attached to the walls of said neck, and with which are connected blowers or fans F, the latter being located on the front portion of the truck of the engine or on any other suitable portion thereof, and having connected with them pipes G, which extend along the engine, and are attached by flexible connections H and short sections of pipes H' with pipes or passages J in the cars K, said pipes having

branches L, which pass under the car-seats for distribution of heat admitted to the pipes J.

In the cars are radiators M, which are in 55 communication with the pipes H' and the pipes or passages J, and contain stoves or other heating devices for obtaining heat should the cars be disconnected from the engine or there be any defective action of the 60 heat generated in the engine. The blowers or fans F are operated by a small engine N, suitably located on the locomotive-engine, the same being under control of the engineer or fireman, if so desired. It will be seen that as 65 air is drawn into the chamber B it is highly heated by contact with the hot flues C and walls of said chamber, and from thence it is driven by the blowers or fans into the pipes G, and thus through the couplings H and 70 pipes H' into the pipes or passages J, the heat entering the radiators M unless directly conveyed by the pipes H' into the pipes or passages J. It will be seen that the cars will be 75 effectively heated, the means employed being simple and inexpensive, easily applied, and without the danger attending the use of stoves.

Connected with the chamber B at or about the place of connection of the pipes E is a 80 valve P, whereby communication of said pipes with the chamber B may be closed, so that heat from said chamber is prevented from entering the pipes E. Valves Q are connected with the pipes E, so that fresh air may be admitted thereinto, whereby provision is made for directing said air into the cars, thus admirably adapting the device to serve as a ventilator or cooler—a feature of service during 85 warm weather.

The shape and location of the chamber B may be varied; hence I do not limit myself to the same; but the shape of the flues is preferably elliptical, so as to gain a large heating-surface without materially affecting the 95 draft of the furnace.

It is evident that by the use of the couplings H and pipes H' the heating-pipes existing in cars may be utilized to receive heat generated in the chamber B. In the present 100 case the chamber B has its casing centrally divided or separated, thus forming a central passage R in front of the boiler flues or tubes for the products of combustion, and increas-

ing the heating-surface of said casing and avoiding interference with the steam-exhaust, draft, &c.

The pipes J and branches I, may have suitable registers for controlling the heat admitted thereinto.

Having thus described my invention, what I claim as new, and desire to secure by Letters Patent, is—

- 10 1. The air-heating chamber B, located in the smoke-box of a locomotive-engine, consisting of a casing with supply-nozzle D, central divisional walls forming the passage R, and a neck A', connecting the divisions of the casing, said passage R being in front of the flues or tubes of the boiler, substantially as described.
- 15 2. The divided chamber B, with air-supply

nozzles D and communicating neck A', in combination with the pipes E, connected with said neck, the distributing-pipes G, extending from said pipes E, and the blowers intermediate of said pipes E G, substantially as described.

- 20 3. The divided chamber B, having the air-supply nozzles D, the communicating neck A', and central passage R, in combination with the flues C, connected with the front and rear walls of the chamber and the smoke-box of a locomotive-engine, substantially as described.

REUBEN E. NICHOLS.
